US00D482973S

(12) **United States Design Patent**
Nottingham et al.

(10) **Patent No.:** **US D482,973 S**
(b4) **Date of Patent:** **** Dec. 2, 2003**

(54) **SQUARE PAINT CONTAINER**

(75) Inventors: **John R. Nottingham**, Hunting Valley, OH (US); **John W. Spirk**, Gates Mills, OH (US); **Dale A. Panasewicz**, Strongsville, OH (US); **Nick E. Stanca**, Westlake, OH (US); **Robert Iredell, IV**, Cleveland Hts., OH (US); **Dennis M. Futo**, Strongsville, OH (US)

(73) Assignee: **NSI Innovation LLC**, Cleveland, OH (US)

(**) Term: **14 Years**

(21) Appl. No.: **29/146,686**

(22) Filed: **Aug. 14, 2001**

(51) LOC (7) Cl. **09-01**

(52) U.S. Cl. **D9/531**; D9/560; D9/575

FOREIGN PATENT DOCUMENTS

CA	800836	12/1968

Primary Examiner—Philip S. Hyder

Assistant Examiner—Carol Rademaker

(74) Attorney, Agent, or Firm—Calfee, Halter & Griswold LLP

(57) **CLAIM**

The ornamental design for a square paint container, as shown and described.

DESCRIPTION

FIG. 1 is a perspective view of the square paint container embodying our design.

FIG. 2 is a front view of the square paint container shown in FIG. 1.

FIG. 3 is a top view of the square paint container shown in FIG. 1.

FIG. 4 is a bottom view of the square paint container shown in FIG. 1.

FIG. 5 is a left side view of the square paint container shown in FIG. 1; and,

FIG. 6 is a right side view of the square paint container shown in FIG. 1.

The broken lines shown in the drawings are for illustrative purposes only and form no part of the claimed design.

1 Claim, 1 Drawing Sheet
